(57) **CLAIM**

The ornamental design for an LED lamp socket, as shown and described.

DESCRIPTION

FIG. 1 is a front view of the invention.

FIG. 2 is a rear view of the invention.

FIG. 3 is a left side view of the invention.

FIG. 4 is a right side view of the invention.

FIG. 5 is a top view of the invention.

FIG. 6 is a bottom view of the invention; and,

FIG. 7 is a perspective view of the invention.

This invention relates to LED lamp socket, particularly an LED lamp socket with innovated design which connected a light-emitting diode module for illumination.

The broken line portion of the figure drawings is included to show portions of the article that form no part of the claimed design.
